PEN

John A. Shea, Jersey City, N. J.

Application June 4, 1938, Serial No. 211,823

7 Claims. (Cl. 120—109)

This invention relates to pens, preferably of stainless steel.

A further object of the invention is to provide a new form of pen which is capable of being used for writing whether in upper or lower position.

The invention consists in a new pen point which is formed by first bending up the lips in V shape, and thereafter completing the bending operation to the finally desired configuration in a manner that no area of metal is between the lips when bent to final shape. The converging form of the final bending provides also an ink reservoir space so as to facilitate the use of the pen.

Finally, the configuration of the bent lips is such that the metal forming the pen point extends away from the inner surface of the pen nib, as also away from the outer surface of the pen nib, whereby, the pen may be used to write in either position of the pen.

The invention will be fully described herein-after, embodiments thereof will be shown in the drawing, and the invention will be finally pointed out in the claims.

In the accompanying drawing:

Figure 1 is a plan view of the inner surface of a completed pen;

Figure 2 is a side view of Figure 1;

Figure 3 is a vertical cross section of Figure 1, taken on line 3—3;

Figure 4 is an enlarged partial view of the nib;

Figure 5 is a cross section on line 5—5 of Figure 4;

Figure 6 is a partial side view of Figure 4;

Figure 7 is a partial plan view of a pen nib with the dot dash line to indicate the inner flow upon which the wings will be bent;

Figure 8 is an end view of Figure 7, when the wings have been bent;

Figure 9 is a side view of Figure 8;

Figure 10 is a vertical cross section taken on line 10—10 of Figure 9;

Figure 11 is a plan view of the nib shown in Figure 1, with a slot cut therein to remove the area of metal indicated by the slot; and

Figure 12 is a plan view of a nib similar to that shown in Figure 7 provided with a sheared slot.

Similar characters of reference indicate corresponding parts throughout the various views.

Referring to the drawing, and more particularly to Figure 11 in which is shown a metal blank of a general V-shaped nib, and with the wings 45 and 46 of the nib portion 47. The

blank has an area of the metal cut out forming the slot 48 as shown in Figure 11.

The next stage after the cut out of the tip slit is to smooth the corners and edge of the tip.

The next stage is to shape the wings 45 and 5

46, and this is done by bending them in V fashion. The wings 45 and 46 are then pressed together in the form shown in Figure 5, by reason of which pressing the V-shaped form is further pressed or bent so as to have the wings 45 and 10 46 substantially parallel with each other, and as considerable pressure is exerted at the very tip of these wings 45 and 46, the tips approach each other very closely, as shown in Figure 4, the space, however, being magnified so as to clarify 15 the exemplification. By pressing the tip portions towards each other, as shown in Figure 4, a space is provided, indicated by 51 in Figure 5, in the upper part of the slot 48, and between the wings 45 and 46, this space serving as a reservoir 20 for the ink. By bending the metal of the wings 45 and 46 from their V shape position closely toward each other, a flow of the metal during this bending action causes the wings to move downwardly below the initial plane of the tip 25 portion, as shown by 52 in Figures 6 and 9.

After the bending has been completed, the pen point or nib is subjected to a slitting action by a shearing scissors or the like, extending from the slot 48 to the pierce hole 42, and a plan 30 view of the pen point with this shear line 57 is shown in Figure 1.

It will here be noted that Figure 5 shows a section taken on lines 5—5, and shows a space between the parts 45 and 46 forming the ink 35 reservoir 51 described. By bending the wings from their initial position shown in Figure 11 to their final position, the flow of metal forms a slight dam indicated by 52b in Figure 2.

It will be particularly noted that in Figure 2 40 the bent up wing portions 45 and 46 form a downwardly extending heel 52 and are rounded at the upper side, as shown by 59, so that the pen point may write on both sides. This hill 59 is shown in somewhat larger size in Figure 3.

The same general shape as shown in Figure 11 is shown in Figure 7, and an imaginary inner flow line of V shape indicated by 60 and 61, with the apex 62 of the V about in line with the narrowest portion 63 of the nib portion 47. The 50 wings 45b and 46b are bent upwardly along these bend lines 60 and 61. After these wings 45b and 46b have been bent upwardly along these bend lines 60 and 61, the rearward parts of the wings contact with each other, and an area of 55

metal remains between the wings 45b and 46b, this area of metal 65 having a curved portion 66. An end view is shown in Figure 8, and the arrows 68 show the flow of the metal. It will be noted in Figure 8 that the lowermost portion 66, which corresponds to the area of metal 65 in Figure 7, becomes bent downwardly below the surface of the nib portion 47, as clearly seen also in Figure 8. These V-shaped bent portions of Figure 7 are then subjected to a flattening pressure so as to bring the wings 45b and 46b closely in contact with each other, as shown in Figure 8. An end view of Figure 9 is shown in Figure 8, and the flow indicated by the arrows 68 to show the manner in which the metal has been subjected to a flow movement. Thus, by pressing these parts together in the manner shown under the flow of metal described, there is an area of metal between the wings. At the same time, the metal which has moved downwardly forms the heel 52 as shown in Figure 9.

The pen shown in Figures 7 and 8 is subjected to a slitting by a shearing action, beginning at 66 and ending at the pierce hole 42 (not shown in Figure 7, but shown in Figures 1 and 2), as indicated by the slit 70 in Figure 10. The pen shown in Figures 7 and 8 is subjected to a rounding action, which will widen out the slit 70 and to some extent open the rearmost parts of the adjacent wings 45b and 46b to form an ink reservoir 51a as shown in Figure 10.

As steel sheets with the hardness of steel pens cannot be bent sharply without cracking, attempts to make steel pens by a continuous machine operation have failed. After considerable research, I have devised the preliminary bending stem in a V shape, which has enabled the pens to be made by a machine in successive stages, without the hand of man touching the metal strip. The continuous method thereby differs from the known method in which a pen blank was cut out and then operated upon by hand operation to complete the individual pen.

In Figure 12 is shown a nib portion 47 with wings 45a and 46a with a shearing slit 49 centrally of the nib portion, this slit 49 and the slot 48 of Figure 11 formed enables the two wings to be pressed together to form cheeks between which a capillary ink conduit is formed, which due to the curved tips may be slightly widened, depending on the pressure applied, even when used front or back. The ordinary pen point opens when used in front fashion, but closes when used in back fashion, whereas the improved pen is usable top and bottom.

From the foregoing, it will have been seen that the improved method differs from other methods heretofore proposed, in that a pen having bent ears may be made in a series of operations in continuity, from a plain metal blank to the finished pen, with the tip portion closely resembling the iridium point of gold pens and having substantially all the advantages thereof, yet being made of stainless steel and by the inexpensive method of manufacture costing but a fraction of such a gold pen. Furthermore, the improved pen differs from pen points heretofore known, in that it first has no area or space between the bent up wings, secondly, that it is first bent in V-shape and then to final form, and is also bent in a manner to provide a lower heel or back so as to enable the pen point to be used both

front or back for two way writing, thus facilitating the use of pen points.

A divisional application Serial No. 238,552 was filed on November 3, 1938, on the method of making pens, which consists in first bending up the lips of a nib to V shape and thereafter completing the preliminary bending operation to the finally desired configuration.

I have described various embodiments of my invention, but it is clear that changes may be made therein without departing from the spirit of my invention as defined in the appended claims.

I claim:

1. A stainless steel pen having a pierce hole 15 consisting of V-shaped wings bent to substantial parallelism without connecting metal between the wings, and shaped above and below the plane of the nib portion, said nib portion having a shearing slit, said slit beginning at the rear of 20 the wings and extending to the pierce hole.

2. A stainless steel pen having a pierce hole consisting of V-shaped wings having a slot between, bent to substantial parallelism without connecting metal between the wings, and shaped 25 above and below the plane of the nib portion, said nib portion having a shearing slit, said slit beginning at the rear of the wings and extending to the pierce hole.

3. A stainless steel pen having a pierce hole 30 consisting of V-shaped wings having a slot between, bent to substantial parallelism without connecting metal between the wings, the formed cheeks forming a capillary conduit, said nib portion having a shearing slit, said slit beginning at the rear of the wings and extending 35 to the pierce hole.

4. A stainless steel pen having a nib in a plane, spaced cheeks extending in both directions of said plane, to enable front and back writing, said 40 cheeks forming a reservoir therebetween permitting ink to flow to the front or back writing surfaces of the nib, the ink of the reservoir extending along the inner faces of the cheeks throughout their area. 45

5. A stainless steel pen having a slotted nib in a plane, spaced cheeks extending in both directions of said plane, the flow of metal of both cheeks being continuous, said cheeks forming a reservoir therebetween permitting ink to flow to 50 the front or back writing surfaces of the nib, the ink of the reservoir extending along the inner faces of the cheeks throughout their area.

6. A stainless steel pen having a slotted nib in a plane, rounded edged cheeks extending above 55 and below said plane, the adjacent faces of the cheeks being inclined in respect to each other, and not contacting and without any area of metal of the pen therebetween, said cheeks forming a reservoir therebetween permitting ink to 60 flow to the front or back writing surfaces of the nib, the ink of the reservoir extending along the inner faces of the cheeks throughout their area.

7. A stainless steel pen having front and back writing portions, curved in contour, spaced to 65 hold the ink therebetween, and yieldable to separate by pressure applied, said cheeks forming a reservoir therebetween permitting ink to flow to the front or back writing surfaces of the nib, the ink of the reservoir extending along the inner 70 faces of the cheeks throughout their area.

JOHN A. SHEA.
